UNITED STATES PATENT OFFICE.

ALBERT GERMAN, OF STEELTON, PENNSYLVANIA.

OIL-BURNER.

1,064,314.

Specification of Letters Patent. Patented June 10, 1913.

Application filed September 11, 1912, Serial No. 719,837.

To all whom it may concern:

Be it known that I, ALBERT GERMAN, a citizen of the United States of America, residing at Steelton, Dauphin county, Pennsylvania, have invented certain new and useful Improvements in Oil-Burners; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention relates to improvements in oil burners, and has for its object to provide a simple and strong construction wherein oil and air may be combined under pressure for the purpose of forming the flame into a sheet, which is especially effective for igniting a mixed charge of ore and fuel in sintering pans, but said burner may also be used for other purposes wherein a sheet of flame is desirable.

20 25 The invention consists in projecting under substantially equal pressures from opposite directions a stream of oil and a stream of air onto deflecting surfaces mounted within a shell or casing, and designed to convert the streams into thin sheets, whereby the oil and air may be more readily combined and converted into a combustible mixture, which issues from the periphery of the shell in a horizontal sheet or series of jets.

30 35 In the accompanying drawing—Figure 1 is a vertical section of one form of burner embodying my invention corresponding to the line 2—2, Fig. 2. Fig. 2 is a top plan view of the bottom plate. Fig. 3 is a vertical section of a modified form of burner. Fig. 4 is a bottom view of the deflecting plate shown in Fig. 3. Fig. 5 is a vertical section of another form of burner taken on line 2—5 of the plate shown in Fig. 2. Fig. 6 is a 45 detail view, partly in section, of a modified form of oil feed-pipe.

40 45 The burner shell consists of a circular bottom plate *a* and a hollow top *b* secured together by bolts *c* passing through holes in the outer edge thereof. The interior of the top is made to provide a hollow space, preferably conical, and has a central screw-threaded aperture through which the oil feed pipe *d* projects, said pipe being screw-

50 threaded to engage the threads of the aperture and the threads of a lock-nut *e* by which the pipe is securely locked in place.

The bottom plate has a central screw-threaded aperture *a'* into which is screwed an air feed-pipe *f*. The plate *a* shown in Figs. 1 and 2 has formed in its top face a series of radial grooves or channels *a*² which extend from the central aperture *a'* to the periphery of the plate.

55 60 65 Mounted on the top face of the plate *a* in the center thereof is a deflecting member, shown as a hollow cone *g* which is held securely in place on the plate by the feed pipe *d* the lower end of which rests on the cone below the apex thereof and is closed thereby. As shown the face of the cone *g* is separated 70 from the interior wall of the top *b* providing an annular chamber or space *h* around the part of the cone which receives the oil from the feed pipe *d*. With the class of oil I have 75 used I have had good results by having the space *h* gradually diminish toward the periphery of the shell. With other classes of oil, tar, etc., it may be necessary to modify 80 the form of the space and vary the convexity of the deflector.

85 90 95 In the specific structure illustrative of my invention the face of the cone *g* lies at a less angle to the face of plate *a* than that at which the interior wall of the top *b* lies, so that an annular chamber *h* is formed around the oil feed pipe *d* which gradually converges toward the periphery of the shell. The pipe *d* communicates with the chamber through a series of apertures *d'* formed in the pipe above its lower end.

100 Oil being supplied to the pipe *d* under pressure, it flows through said apertures onto the top of the cone. The air is introduced under substantially the same pressure, through the pipe *f* under the cone, and is deflected by the latter downward onto the plate *a* and escapes from under the cone through the grooves or channels *a*², and combines with the oil at the lower edge of the cone, forming a readily combustible mixture which is forced beyond the periphery of the shell, and when lighted will burn in the form of horizontal jets.

105 In the form shown in Figs. 3 and 4, means are provided for supplying the oil and air mixture in a thin sheet instead of a plurality of jets. This is accomplished by

forming the top of the bottom plate a^3 with a smooth surface and raising the flange of the top b above the plate by resting it on washers i which surround the bolts c . The deflecting cone g' is provided with a plurality of lugs or feet g^2 formed on the underside thereof and projecting below the lower edge sufficiently to hold the latter from contact with the top of the plate a^3 . Thus a substantially uninterrupted passage for the air is provided between the pipe f and the periphery of the shell.

Fig. 5 illustrates a modified form of oil feed, wherein the oil flows from the bottom 15 of the pipe d^2 which is raised above the cone. To secure an accurate centering of the deflecting cone the pipe d^2 may first be screwed down onto said cone, and then the set screws j mounted in the top b are screwed 20 down onto the cone to hold it in place, whereupon the pipe d^2 is raised into operative position. It is possible by this means to readily regulate the flow of oil through the pipe. The bottom plate in this form is 25 the same as that shown in Fig. 1, but the bottom plate and deflecting cone shown in, Fig. 3 may be substituted therefor.

Instead of the aperture h shown in Figs. 1 and 3 the lower end of the feed pipe d 30 may be provided with a plurality of notches d^3 as shown in Fig. 6. In Figs. 1, 3 and 6 the pipe d holds the conical deflecting member in position.

I claim—

35 1. In an oil burner, a stationary shell consisting of a bottom plate, a hollow top arranged thereon and forming therewith a central chamber having a narrow peripheral radially directed aperture, an air supply 40 pipe entering through an aperture in said bottom plate, an oil supply pipe projecting through a central aperture in the top, and a cone-shaped deflecting member having its apex centered in the end of the oil supply 45 pipe and its periphery in the plane of said aperture.

2. In an oil burner, a shell consisting of a bottom plate, a hollow top arranged thereon and forming therewith a central chamber 50 having a peripheral aperture, an air supply pipe entering through an aperture in said bottom plate, an oil supply pipe having apertures near its end and projecting through a central aperture in the top, and 55 a hollow cone-shaped member having its

end seated in the discharge end of the oil supply pipe.

3. An oil burner comprising a circular bottom plate having a plurality of radial grooves formed in its upper face, a hollow member having a flange resting on the top face of the plate, an oil supply pipe having discharge apertures near its end and projecting through a central aperture in the top of the hollow member, a hollow conical member mounted on the top face of the bottom plate and having its apex projecting into the oil pipe, and an air supply pipe entering an aperture in the bottom plate.

4. An oil burner comprising a circular bottom plate having a central aperture and a plurality of radial grooves in its top face extending from said aperture to the periphery of the plate, a hollow member having a flange seated on the bottom plate and having a central aperture, an oil supply pipe having discharge apertures near its end and projecting through the aperture in the hollow member, a hollow conical deflecting member mounted on the top face of the plate 75 and having the apex projecting into and closing the end of said pipe, and an air pipe mounted in the aperture of the bottom plate.

5. In combination, a casing comprising two members, one of which is a flat plate 85 and the other member being conical and having a flange at its base, a narrow radially directed discharge passage between the plate and casing, supply pipes centrally secured in the members, a conical deflector, one of 90 said pipes engaging the apex of the deflector and holding it against the flat plate and centrally of the conical member, the edge of said deflector lying in the plane of said discharge passage.

6. The combination with a casing comprising a flat member and a frusto-conical member; of a supply pipe for oil connected to one member and a supply pipe for air connected to the other member, and a conical deflecting member held centered against the flat member by the supply pipe of the other member.

In testimony that I claim the foregoing as my invention, I have signed my name in 105 presence of two subscribing witnesses.

ALBERT GERMAN.
